ABRADING WHEEL

Loren E. Thompson, Parkersburg, W. Va.

Application October 14, 1942, Serial No. 462,009

1 Claim. (Cl. 51—209)

This invention relates to abrading grinding wheels, and is a division of my co-pending application Serial Number 309,290, filed December 14, 1939, for Abrading apparatus.

An object of this invention is to provide a new and improved means for mounting an abrader wheel or disc in a holder.

Another object of this invention is to provide an improved chuck for removably holding an abrader disc.

A further object of this invention is to provide an improved holder for a surfacing abrader in which the holder is constructed in the form of a flanged plate provided with releasable clamping means for the abrader, the holder being of such construction that when the abrader is mounted therein the abrader can be used in precision grinding.

The invention consists of the novel construction, combination and arrangement of parts as will be more specifically referred to and illustrated in the accompanying drawing, wherein is shown an embodiment of the invention, but it is to be understood that changes, variations and modifications may be resorted to which fall within the scope of the invention as claimed.

In the drawing:

Figure 1 is a fragmentary front elevation, partly in section, of an abrader and chuck constructed according to the embodiment of this invention.

Figure 2 is a sectional view taken on the line 2—2 of Figure 1.

Figure 3 is a fragmentary sectional view taken on the line 3—3 of Figure 1, and

Figure 4 is a fragmentary enlarged sectional view showing one of the abrader clamping members.

Referring to the drawing, the character G designates a holder consisting of a circular disc-like body 1 having a rearwardly directed centrally disposed reinforcing portion 2 which is of circular form and tapered. The body 1 is formed axially thereof with a threaded bore 3 for a purpose to be referred to. The bore 3 extends from the rear surface of portion 2 to the forward face 4 of body 1. Formed integral with the outer marginal portion of the forward face 4 and flush with the outer edge of body 1 is a forwardly directed annular rim 5 provided at equi-distant spaced points with inwardly opening pockets 6 (Figure 4), preferably four in number. It is to be understood that the number of pockets 6 may be as desired.

Arranged within the pockets 6 are adjustable

combined centering and holding members 7, for a purpose to be referred to. The members 7 are of a contour corresponding to the segment of a circle and are mounted slidably in the pockets 6 for adjustment. The members 7 are of uniform thickness and each is of rectangular contour in transverse cross section. The inner and outer faces 8 and 9 of each member 7 are of greater width than the side surfaces 10 and 11 of the latter. The inner surface 8 of each member 7 is the working face thereof. The rim 4 is formed with spaced pairs of spaced threaded openings. The openings of each pair are indicated at 12 and 13 and extend from the outer side face of rim 4 to and communicate with a pocket 6 at the base of the latter.

Threadedly engaging with the openings 12, 13 of each pair is a pair of combined adjusting and clamping screws 14, 15, respectively, for a member 7. A pair of screws 14, 15 abut the outer face of a member 7 for shifting it relative to an abrader or grinder 16 arranged in holder G, for adjusting abrader 16 to center it with respect to said holder G and for maintaining the abrader 16 in its adjusted position. The abrader 16 is in the form of a circular body 17 of any suitable abrading material and is of a thickness to project outwardly with respect to the forward edge 18 of the rim 5. Encompassing the abrader 16 and of a width to extend from the forward face 4 of body 1 to the edge 18 of rim 5 is a thin annular liner 19 against which the members 7 bear. The liner 19 opposes the edge 22 of rim 5. Preferably, the liner 19 will be formed of paper, but it is to be understood that it may be formed from any suitable material.

The rim 5 in connection with the body 1 forms a circular cavity 21, with the base wall and side wall of the latter provided, respectively, by the forward face 4 of body 1 and the inner edge 22 of rim 5. The liner 19 is arranged against the edge 22 before the abrader 16 is mounted in holder G. After the liner 19 has been arranged relative to rim 5, the abrader 16 is then pressed into the holder G against the liner 19 and to an extent to engage the forward face of body 1. This manner of mounting abrader 16 compresses and provides for the liner 19 sealing the abrader 16 in the cavity 21 with a vacuum tight grip.

The abrader 16 is in the form of an emery or carborundum wheel and is bored axially as at 23. The outer diameter of the abrader 16 with respect to the diameter of the cavity 21 is such that when abrader 16 is pressed into the holder G, it will provide for wedgily binding the liner

19 in encompassing relation with respect to the abrader and against the rim. The members 7 also act on the liner 19 in a manner to prevent the abrader 16 from slipping or turning inside of and relative to holder G when a severe thrust is applied at or near the rim of such holder.

In the use and operation of the abrading element G, the liner 19 is placed in the socket or recess 21 formed by the annular flange or rim 5. The clamping segments 7 are retracted by loosening the clamping screws 14 and 15, and then the abrader 16 is pressed into the socket 21. The screws 14 and 15 are then tightened to force the segments 7 inwardly against the liner 19 and press the liner 19 against the cylindrical outer side of the abrader 16. The abrader 16 has a thickness in excess of the depth of the socket 21 so that a sufficient amount of the abrader 16 projects outwardly of the flange 5 to provide a grinding or surfacing face, it being understood 20

that the outer end or face of the abrader 16 constitutes the working face.

What I claim is:

In combination, a holder formed of a disc-shaped body, an annular flange carried by said body, a disc-shaped abrader seated in said flange and having a portion thereof projecting from said flange, a fibrous liner fixed to the periphery of said abrader, said flange having a plurality of 5 inwardly opening circumferentially spaced apart recesses therein, segmental clamping members slidably mounted in said recesses, and set screws threaded through said flange from the outer side thereof engaging against said clamping members 10 for holding the latter tight against said liner, said set screws at their outer ends terminating 15 substantially flush with the outer surface of said flange.

LOREN E. THOMPSON.
